JOSEPH N. MAHONEY, OF BROOKLYN, NEW YORK, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS

CIRCUIT INTERRUPTER

Application filed June 27, 1925. Serial No. 40,030.

This invention relates to electric circuit interrupters and has for an object the provision of means to introduce an impedance into the circuit during circuit interruption whereby to reduce the amount of energy to be interrupted.

A further object of the invention is generally to improve the construction and operation of circuit interrupters.

The broad idea of rotating the circuit interrupting arc is disclosed in the co-pending applications of Talma T. Greenwood, Serial No. 755,353, filed December 11, 1924; and Serial No. 33,848, filed May 29, 1925, and assigned to the assignee of this application.

Fig. 1 is a sectional detail illustrating the stationary and movable members of the circuit interrupter in the closed position thereof.

Fig. 2 is a view similar to Fig. 1 but with the impedance introduced into the circuit and prior to complete circuit interruption.

Fig. 3 is a view similar to Fig. 2 but illustrating the complete open circuit position of the circuit interrupting members.

Fig. 4 is a sectional elevation illustrating a modified form of the invention.

Fig. 5 is a view similar to Fig. 4 but illustrating the relation of the parts in open-circuit position.

Fig. 6 is a modified form of the structure illustrated in Fig. 1 wherein the impedance is arranged to short-circuit itself in the closed condition of the interrupter.

In the construction illustrated in Figs. 1, 2 and 3, the circuit interrupter includes a stationary switch terminal including an insulator 10 which surrounds a conducting stud 12. A plate 14 is electrically and mechanically connected with the lower end of said switch stud. A housing 16 is secured fixedly and preferably removably to the lower face of said plate 14 by suitable means as by the bolts 18. A multi-part fixed contact member 20 is disposed within said housing and the parts thereof are held yieldingly in contracted position by suitable means as the encircling coil spring 22.

In accordance with this invention, an impedance member is associated with the interrupter and is adapted to be included in the

circuit through the interrupter at the period of circuit interruption whereby to choke down the amount of energy to be finally interrupted at the circuit-interrupting arc. As here shown, the impedance is helical in form and comprises a plurality of convolutions 24 which may normally assume a more or less cylindrical form. Said impedance member may be composed of any suitable resistance material, as, for instance, spring steel and, in addition to having resistance, also has reactance by virtue of its convolutions. The resilient convolutions, in the closed condition of the interrupter, are adapted to be disposed in closed order, or in actual mechanical and electrical contact, as indicated in Fig. 1 but when the interrupter is operated to interrupt the circuit, said convolutions are adapted to open up as illustrated in Figs. 2 and 3.

Said impedance element preferably is coaxially disposed with the passage through the stationary contact member 20, and depends therebelow. An upper convolution 24 thereof may be retained in spring-pressed engagement in a groove of an annular flange 26 of the housing 16 whereby to support the impedance in the aforesaid relation. In the closed condition of the interrupter, said impedance member is adapted normally to be short circuited and thereby cut out of the circuit through the interrupter. To this end one of the lower convolutions of the impedance member is secured to an annular flange 28 of a secondary or intermediate movable contact member 29 which also constitutes a circuit-interrupting arcing member, and which has a stem 30 extended upwardly in position to enter and engage the fixed contact member 20. Said stem 30 is hollow and is adapted to receive the movable circuit-interrupting arcing member 32 of the interrupter. In the normally closed condition of the interrupter, the impedance member is short circuited by the engagement of the secondary contact member 29 with the fixed contact member and the current traverses the switch through said two contact members and the movable contact member 32 and excludes the impedance. When the circuit interrupter is operated to 100

interrupt the circuit, the movable contact member is lowered. Due to the resiliency of the impedance member, the secondary contact member is maintained in position on the upper end of and in contact with the movable circuit-interrupting arcing member and is thereby withdrawn from the fixed contact member 20, thereby introducing the impedance member actively in the circuit. At the moment of separation of the fixed and secondary contact members an arc may take place and the extent of separation of said members is adapted to be sufficient to cause the extinguishing of the arc. A continued downward movement of the movable circuit-interrupting member effects its separation from its cooperating circuit-interrupting member 29 and a circuit-interrupting arc may be drawn between said two members. The arc will be extinguished by reason of its attenuation and the cooling effect of the bath of oil or other arc quenching fluid in which the contact members may be immersed.

Under certain circumstances, it may not be necessary to provide short-circuit contact members for the impedance member. In the construction illustrated in Fig. 6, for instance, when the circuit interrupter is closed, the convolutions of the impedance member are adapted to be pressed forcibly into electrical contact with each other, so that the convolutions short circuit themselves.

In the modifications illustrated in Figs. 4 and 5, the convolutions 24a of the impedance member are arranged in concentric and approximately flat form in the closed position of the interrupter and each convolution is arranged to be in independent contact with the lower face of the housing 20a. As thus arranged, during the opening movement of the interrupter, the convolutions separate in progressive order from said housing and thereby gradually and progressively introduce the impedance into the circuit.

The resilient impedance member also serves as a spring to speed-up the opening movement of the movable circuit-interrupting arcing member.

Said impedance member also acts as a solenoid to effect the rotation of the circuit interrupting arc between the circuit-interrupting arcing members whereby to enhance the speed of circuit interruption.

The helical spring provides for a universal movement of the contact member carried by it, by which the contact member can align itself with its cooperating contact member, when one is moved into the other.

The construction may be otherwise modified without departing from the spirit of the invention.

I claim:

1. A circuit interrupter comprising separable contact members, separable arcing members affording an endless path for an

arc draw therebetween, and means for inserting current-limiting impedance between said contact members when the latter are separated and for providing an arc-rotating field to rotate the arc drawn between said 70 arcing members.

2. Means for interrupting an electric circuit comprising a current-limiting impedance which also provides an arc-rotating field, a pair of arcing members in said circuit, and 75 means for separating said arcing members to establish an arc therebetween in such relation to the field of said impedance that the arc is rotated thereby.

3. An electric circuit interrupter including 80 an interrupter terminal having a fixed annular contact, a flexible helicoidal current-limiting impedance having its upper end supported by and electrically connected with said terminal, said current-limiting impedance also providing an arc-rotating field, an annular circuit-interrupting arcing member carried by and electrically connected with the lower end of said helicoidal impedance and adapted to engage within said annular 90 contact, and a movable circuit-interrupting arcing member to control the circuit through said impedance and also through the interrupter engageable within said annular circuit-interrupting arcing member, said arcing 95 members affording an endless path for the arc drawn therebetween whereby the arc can be rotated by the field of said impedance.

4. An electric circuit interrupter including 100 an interrupter terminal, a flexible helicoidal current-limiting impedance having its upper end supported by and electrically connected with said terminal, said current-limiting impedance also providing an arc-rotating field, an annular circuit-interrupting arcing 105 member carried by and electrically connected with the lower end of said helicoidal impedance, and a movable circuit-interrupting arcing member to control the circuit through said impedance and also through the interrupter engageable within said annular circuit-interrupting arcing member, said arcing members affording an endless path for the arc drawn therebetween whereby the arc can be rotated by the field of said impedance. 110

5. An electric circuit interrupter including 115 an interrupter terminal, a flexible helicoidal current-limiting impedance having one end thereof electrically connected to said terminal, a circuit interrupting arcing member electrically connected to the other end of said helicoidal impedance comprising a hollow stem concentric with said impedance and having a flaring opening, and a movable circuit interrupting arcing member engageable within said hollow stem and movable through said flared opening to interrupt the circuit, said arcing members having such an arrangement with respect to each other and to said 120 impedance that the arc drawn between said 125 members affording an endless path for an

arcing members is traversed by the field of said impedance and rotated thereby.

6. An electric circuit interrupter including a member having the combined properties of a current-limiting impedance and a rotator for the circuit interrupting arc, a fixed contact member and circuit-interrupting arcing members, affording an endless path for the arc, one of said circuit interrupting arcing members engageable with said fixed contact member and with the other arcing member, said arcing members having their arcing surfaces so arranged with respect to each other and said impedance that the arc drawn between them is traversed by the field of said impedance and rotated thereby.

7. An electric circuit interrupter including a member having the combined properties of a current-limiting impedance and a rotator for the circuit interrupting arc, and cooperating arcing members affording an endless path for the arc engageable with and disengageable from each other to close and open the circuit and constructed and arranged so that the arc drawn between them is traversed by the field of said impedance and rotated thereby.

In testimony whereof, I have signed my name to this specification.

JOSEPH N. MAHONEY.
